NOBUTARO MONOBE, OF TOKYO, JAPAN, ASSIGNOR TO EIZO HAYASHI, OF TOKYO,
JAPAN.

MOLD FOR CASTING TYPES.

Application filed February 27, 1925. Serial No. 12,115.

To all whom it may concern:

Be it known that I, NOBUTARO MONOBE, a subject of the Emperor of Japan, residing at No. 12, 2-Chome, Ichibeye-cho, Azabu-ku, Tokyo, Japan, have invented new and useful Improvements in a Mold for Casting Types, of which the following is a specification.

This invention relates to a mold for casting types consisting of a mold proper divisible into two, one part of which contains three sides of a casting cavity and the other part forms the fourth side, so arranged that the latter closes or opens the cavity by sliding, the former being provided with rods at the opposite side of the sliding member, and when a type is cast and the cavity is opened, the rods pushing the cast type out of the cavity, and ducts within the body of the mold proper connected with water pipes to circulate cooling water, and the object of this invention is to provide a mold for casting types rapidly of a hard metal of a high melting point in accurate size and shape.

The accompanying drawings show an example of a type-casting machine constructed according to this invention. Figure 1 shows an elevation of the machine with some part broken away; Fig. 2 the side view with some part shown in section; Fig. 3 is a front view of the mold; Fig. 4 a side elevation; Fig. 5 a horizontal section on the line V—V in Fig. 3; Fig. 6 a front view of the main body of the upper mold; Figs. 7 and 8 are vertical sections respectively on the lines VII—VII and VIII—VIII in Fig. 6; Fig. 9 is a perspective view of a sliding plate or the lower mold; Fig. 10 a perspective view of a piece which is attached to, and forms part of the upper mold; Fig. 11 a front view of the mold bed; Fig. 12 a vertical section on the line XII—XII of Fig. 11; Fig. 13 a front view of a modified construction of the upper mold; and Fig. 14 a section of the same.

In the Figs. 3 and 4, (1) is the upper mold, (2) the mold bed, (3) the lower mold which slides between the upper mold (1) and the mold bed (2), (4) a cavity for casting formed between the upper and the lower molds. The molten alloy is to be injected into the cavity (4) through a port (5) provided at one end of the mold, thus types being cast. The three sides of the above-mentioned cavity are formed in the upper

mold (1) and the other side, by the lower mold (3), the end to be closed by a matrix (6) shown in Fig. 2. If the lower mold (3) slides to the right in Fig. 3, the bottom of the cavity will be opened. The upper mold is provided with a groove (8) on the bottom surface across the above mentioned cavity, which groove fitting a projection or ridge (7) of the lower mold. The port (5) makes a step with the end of the cavity (4), and is formed by inclined planes. It is thus difficult to make them integral with the mold. It is therefore preferably made in a piece (9) as shown in Fig. 10 which is to be fixed with screws to the side of the main body of the upper mold (1). A rectangular projection (10) is provided at the central portion of the bottom surface of the upper mold (1). Inside the upper mold a circular channel (11), both ends of which are closed, is bored near the cavity (4), and two ducts (12) and (13) perpendicular to and communicating with the channel (11), are provided. (14) and (15) are water pipes which are connected respectively to the ducts (12) and (13), and cooling water is circulated through them. The upper wall of the cavity (4) is provided with vertical holes for rods (16) which are at such position that their lower ends are in the same plane with the upper surface of the cavity (4) during the injection of molten metal; but after the injection the rods moving downwards, push the cast type out of the mold. As shown in Fig. 9 the bottom mold (3) has thickness slightly greater than the width of type and is provided with a rectangular hole (17), the width of which corresponds to that of projection (10) at the bottom of the upper mold and the length is longer than that of the latter. The upper surface of the lower mold is provided on one side with a ridge (7) which fits the groove (8) on the lower surface of the upper mold and on the other side there is a projection (18) which comes in contact with the bottom of the piece (9) attached to the upper mold and forms the bottom of the port (5), the lower surface being simply a plane. The upper surface of the mold bed (2) is provided with a shallow indentation (19) in which the bottom of the projection (10) of the upper mold is seated, and holes (20) for screws which fix the upper mold at its position. The downwardly extending portion (21) of the bed is used

for fixing it to the machine frame. The bed has water passages (22), (23), and (24) in the interior similarly situated as the passages (11), (12), and (13) in the upper mold and are connected with the water pipes (25) and (26).

In Figs. 13 and 14 a machine is shown in which the upper mold of the main body is made divisible into two parts (1) and (1'). The part (1') is a flat plate equal in thickness to the height of types to be cast, inserted between the part (1) and the lower mold (3), and has a projection (46) at the other end, which is inserted between two projections (47) and (48) of the part (1), being moved by adjusting screws (49) and (50) so as to adjust the width of the cavity (4) and consequently that of types to be cast.

The mold is completed by fixing its various parts as described in their places. The piece (9) is fixed at one side of the upper mold (1), the bottom projection thereof being inserted in the indentation (19) of the mold bed (2) and secured with screws, and the projection (10) penetrating into the lower mold (3) through the rectangular hole (17). Thus the lower mold (3) which lies between (1) and (2) can slide from left to right and vice versa. If the lower mold as shown in Fig. 3 slides to the right, it opens the bottom of the cavity (4), and by the downward motion of the rods (16) the cast type is pushed down and drops on the bed (2), and then delivered out of the mold in its return motion to the left.

Figs. 1 and 2 show an example of my type-casting machine equipped with the mold described before, in which (27) is an alloy melting pot, (28) a tapping hole, (29) a needle valve which controls the supply of melted metal, (30) a piston which forces out the melted metal, (31) a mold holding frame hinged to the main frame with the pin (32), (33) a matrix holding frame hinged to the former with the pin (34), and (35) a cam shaft. The above mentioned mold is clamped to the mold holding frame (31) with screws at the downwardly extending portion (21) and the matrix (6) is fixed to the holder (33). Several cams are fixed to the cam shaft (35) (though not shown in the figures), and revolution of these cams forces the matrix (16) to come in contact with the end of the mold (4) and the mold with the tapping hole (28). Next the needle valve (29) goes back and opens the tapping hole by the action of another cam and lever, and the piston (30) forces the molten metal into the mold through the tapping hole. Then the mold holding frame and the matrix holder returning to their former position by the action of the cams and springs, are separated from the tapping hole and kept apart. A grooved cam (36) is fixed to the cam shaft

(35) together with previously described cams, and a roller (39) at the lower end of a lever (38) is pivoted to the mold holding frame with a pin (37) and is fitted to the groove. The upper end of the lever (38) has another roller (40), and a connecting rod (41) connects the lower mold (3) to the lever (38). (42) is a bracket fixed above the upper mold (1) and supports a lever (43), one end of which is connected to the push rods (16). The other end of the lever (43) is enlarged and provided with a slot (44), to which the above mentioned roller (40) is fitted, and the middle portion of which has inclination as shown at (45).

When the frames (31) and (33) are forced to be in contact with the tapping hole (28), and the molten metal is injected as previously described, the lever (38) is at such a position as shown in Figure 1. The shape of the groove of the cam should be determined in such a way that soon after the completion of tapping and of the return motion of the frames to the position shown in Fig. 2, the bent portion of the groove goes into action on the roller (39) of the lever (38), and the upper end of the latter swings to the right in Fig. 1 and immediately returns back to the original position. Therefore the lower mold (3) closes the bottom surface of the upper mold and the rods (16) are at such positions as the lower ends are in the same plane with the upper surface of the cavity (4) when the frames (31) and (33) are forced to contact with the tapping hole and the molten metal is injected into the mold (4) by the piston. After the frames (31) and (33) return to the positions shown in Fig. 2 the motion of the lever (38) actuated by the cam (36) will move the lower mold (3) to the right through the connecting link (41) and open the bottom of the mold. The roller (40) gives no influence on the lever (43), simply moving in the slot (44) until the lever (38) takes this position. But as soon as the lower mold opens the bottom of the upper mold, the roller (40) reaches to the inclined portion (45) of the said slot (44) and pushes it. Thus the other end of the lever (43) moves downward and projects the rods (16) into the mold. Consequently the cast type is dropped on the upper surface of the mold bed (2). Then in the return motion of the lever (38), the rods ascend and the lower mold removes the type from the mold bed by its own sliding motion to the left. The type is next worked by the other finishing mechanism, i. e. the cutting away of sprue and is then completed. While the casting is going on, the cooling water is circulated by the action of the pump attached to the machine through the upper mold passage consisting of the pipe (14) the holes (12), (11), and (13), and the pipe (15) and the lower mold bed passage consisting of the

pipe (25), the holes (23), (22), and (24), and the pipe (26), in order to cool the mold perfectly.

As hereinbefore described, the mold according to this invention consists of two parts, (1) and (3).

As the groove which shapes the three sides of the type is provided in the part (1) and the other one side is formed by the part (3), and as the latter opens the said groove by sliding parallel to the bottom surface of the part (1), the joint of the molds always closes accurately, and the type is not only made in accurate form and size, but also the molten metal does not leak out of the joint and makes no projection on the corner so that no finishing is needed on the side surfaces of the type. As previously described, the cast types are not dropped from the mold bed but forced to slip out, so they can be brought in regular series along the guide plate connected to the upper surface of the mold bed to the finishing apparatus to cut sprue if such apparatus is attached.

Also the molds hitherto in use have no room for a perfect cooling apparatus so that the casting is very difficult unless the melting point of the alloys used is low. But in the mold according to this invention, the upper mold and its bed are equipped with water passages through which cooling water circulates so that the mold can be perfectly cooled. Therefore the casting of the hard metal types using the alloys of high melting point which have hitherto never been used, becomes possible.

In this specification, the words "upper mold" "lower mold" etc. are conveniently used according to the positions shown in the illustrations as an example, but the relations of position are not important and the two parts of the mold are not necessarily required to be placed up and below.

Claims:

1. A mold for casting printing types consisting of two mold members, one of which having three sides of a casting cavity, the other being a plain plate which forms the fourth side of the same cavity, means to move the latter along the former, thus opening the above mentioned cavity to permit the cast type to move out of the mold.

2. A mold for casting printing type consisting of two mold members, one of which having three sides of a casting cavity, the other, being a plain plate slidably inserted between the said member and a mold bed to which the former member is fixed, and after the sliding member opens the bottom of the mold as the result of its sliding

away, the cast type is pushed out of the mold and laid on the mold bed, and then delivered from the bed by the sliding member.

3. A mold for casting printing types consisting of an upper mold member which have the three sides of a casting cavity, one of which being adjustable by screws; a slidable lower mold member which forms the fourth side of a casting cavity, means to move the latter along the former, thus opening the casting cavity and delivering the cast type out of the mold; and cooling water passages.

4. A mold for casting printing types consisting of two mold members, one of which have three sides of a casting cavity, the other being a plain plate which forms the fourth side of the said cavity; means to move the latter along the former, thus opening the above mentioned cavity and rods to push out the cast type, the said sliding member thus delivering the cast type out of the mold, and cooling water passages, the sliding mold member being connected to a lever and the pushing rods to another lever the other end of which having a curved groove to which a projection of the other lever is inserted.

5. A mold for casting type including a first mold section provided at its bottom with a cavity, a plate closing the mouth of said cavity, means for moving one of the sections relatively to the other to open the mouth of the cavity, means for forcing a cast type out of the cavity when its mouth has been opened, the movable section being arranged to eject the cast type from the mold after it has been forced out of said cavity.

6. A mold for casting type including a support, a flat plate slidably mounted on said support and provided with a slot and ridge, a stationary mold member arranged above the plate and provided on its bottom with a cavity, the mouth of which is normally closed by said plate, a bar connected to the upper mold member and extending through the slot in the plate for guiding the latter, said upper mold member having a groove into which the ridge extends, means for ejecting a cast type from said cavity when the plate has been slid out of the way to permit the cast type to fall onto said support, the plate functioning to eject the cast type from between the support and upper mold member when the plate moves in one direction.

In testimony whereof I have signed my name to this specification.

NOBUTARO MONOBE,
